UNITED STATES PATENT OFFICE.

JOHN S. CLEVELAND AND GEORGE F. KENT, OF NORRIDGEWOCK, MAINE.

INSULATOR.

SPECIFICATION forming part of Letters Patent No. 307,916, dated November 11, 1884.

Application filed February 23, 1884. (No model.)

To all whom it may concern:

Be it known that we, JOHN S. CLEVELAND and GEORGE F. KENT, citizens of the United States, residing at Norridgewock, in the county of Somerset and State of Maine, have invented certain new and useful Improvements in Insulators; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Our invention relates to insulators; and it consists in the construction, combination, and arrangement of the several parts, as will be hereinafter described and claimed.

In the drawings, Figure 1 is a perspective view. Fig. 2 is a transverse section. Fig. 3 is an end view. Fig. 4 is a top plan view. Fig. 5 is a side elevation of our improved insulator, all of which will be described.

The insulator-blocks A A are made of glass or other suitable material. In operation they are held with their ends close together. These meeting ends are provided with coincident grooves A', preferably curved to fit the wire B, and one or both are made of a depth less than the semi-diameter of said wire, as shown, so that when pressed together they will firmly clamp and hold the said wire. This obviates the winding of the wire on the insulators, and thereby economizes the length of wire, the wear of same incident to its bending, and does away with the necessity of wire for binding the electric wire to the insulator, as is sometimes practiced, instead of winding the electric wire on the insulator, as will be understood.

40 It will be observed that our invention, broadly speaking, comprises two insulator-blocks adapted at their meeting ends to clamp the wire, combined with the means for clamping the said blocks together.

45 The supporting and block-clamping devices may, it is manifest, be constructed in various ways without departing from the principles of our invention; but in practice we prefer to construct said devices as shown and will be now described.

The support or casing C is provided with a longitudinal mortise, C', extended from one

end, as shown. This mortise is fitted to receive the insulating-blocks, and is provided with a groove or keyway, C'. The insulating-blocks are made with a key, A², which slides in said keyway and prevents the rotation of the blocks when the latter are made cylindrical. When the said blocks are made angular in cross-section, such keyway and rib or key will not be required. A transverse slot, D, intersects the mortise C' from the upper side of the casing about midway the ends of same. This slot is so formed as to permit the wire to be inserted between blocks A from above, and also to form space on opposite sides of the wire as the latter extends outward from the blocks, so as to prevent the current passing off through the support or casing. A cross-bar, E, is removably secured at the end of the casing at which mortise C' opens, and extends across said slot or mortise, as shown. We prefer to secure this key by passing it through the slots E' in the casing, as shown. A set-screw, F, turns through the bar E and bears against the outer one of blocks A, forcing it against the inner blocks, clamping the wire securely thereto, as will be understood.

For convenience in securing the support to the pole or in other desired position, we provide it with perforated lugs or ears, G G, through which retaining-screws may be passed.

It is manifest that instead of the cross-bar or key and set-screw, as shown and described, various modified constructions may be employed without departing from the broad principles of our invention. An opening, H, is formed through the casing at the base or inner end of mortise C', so the hand or a suitable implement can be pressed against the inner block and force the blocks out of the casing when so desired.

Having thus described our invention, what we claim, and desire to secure by Letters Patent, is—

1. The insulator herein described, consisting of the casing mortised from one end to receive the blocks, and provided with a transverse slot intersecting said mortise at a point approximately midway the same, and the insulating-blocks held in said mortise with their meeting faces opposite the intersecting slot, substantially as set forth.

2. In an insulator, the combination, with

the casing having a longitudinal mortise, and provided with slots near the outer end thereof, and the blocks placed in said mortise and adapted at their meeting ends to clamp the 5 wire, of the cross-bar removably held in the slots of the casing, and the set-screw turned through said bar in position to bear against the outer block, substantially as set forth.

3. The combination of the casing mortised 10 from one end, the insulating-blocks inserted in said mortise, a removable bearing-bar, and a clamping-screw turned through said bar and against the adjacent insulator, binding 15 said parts firmly together, substantially as set forth.

4. The combination of the casing having a longitudinal mortise, C^o, formed with a wing or keyway, C^o, and the insulating-blocks inserted in said mortise, and formed with a rib 20 fitted to the keyway thereof, substantially as set forth.

5. An insulator comprising a supporting-frame, insulating-blocks having at their inner faces grooves adapted to fit on the wire and made of a depth less than the semi-diameter 25 of the said wire and in continuous unbroken coincident lines, and the clamping-screw turned against one of these blocks and pressing the same toward the other and on the wire, whereby the latter is firmly held, the said clamping 30 action or strain being exerted in a line approximately radial to the wire, whereby the torsional strain of the said wire will not affect the clamping thereof, substantially as set forth.

In testimony whereof we affix our signatures 35 in presence of two witnesses.

JOHN S. CLEVELAND.
